UNITED STATES PATENT OFFICE.

ANTOINE ANDREANI, OF GENEVA, SWITZERLAND.

LOCK.

1,379,844.

Specification of Letters Patent. Patented May 31, 1921.

Application filed June 28, 1920. Serial No. 392,272.

To all whom it may concern:

Be it known that I, ANTOINE ANDREANI, of Geneva, Switzerland, a subject of the King of Italy, have invented certain new and useful Improvements in Locks, of which the following is a specification.

The invention relates to locks of the type wherein a barrel is normally locked, against rotation, by means of sliders adapted to be retracted by means of the key.

According to the invention the sliders are small rods or cylinders disposed in two rows in the barrel, at opposite sides of the key way, the sliders in these two rows being thrust in opposite directions by springs, to engage a shell or casing inclosing the barrel, and each slider having a lateral projection extending into the key-way so disposed that insertion of the key retracts the several sliders to the proper extent. The lateral projections may be in the form of hooks, oppositely bent as regards the two rows, the key having two side plates which engage under these hooks and an undulating web which penetrates between the tips of the hooks and thus effects the retraction.

The invention is illustrated in the annexed drawings, showing two forms of construction in Figures 1 to 7 and in Figs. 8 and 9 respectively.

Fig. 1 is a cross section of the lock on the line A—A of Fig. 2.

Fig. 2 being a longitudinal section, showing the sliders in the locking position.

Fig. 3 is a longitudinal section, and Fig. 4 a cross section, showing the lock with the key inserted and the tumblers retracted.

Fig. 5 is an elevation of the key and Fig. 6 a cross section thereof.

Fig. 7 is an elevation of the shell, with the sheath removed.

Fig. 8 is a cross-section of the barrel in the second modification, and

Fig. 9 is a plan view thereof.

Referring in the first instance to Figs. 1 to 7, *a* designates the shell, *b* the sheath, *c* the barrel and *d* the sliders. The sliders are disposed in two parallel rows at the sides of the key-way in the barrel. Each of the sliders is acted on by a spring *e*, tending to thrust it into a hole *f* in the shell, the sliders in the two rows moving in opposite directions. The spring is coiled upon a shank *g* of the slider, which is in line with a hole *m* in the shell. The key consists of a handle and two parallel narrow side plates or strips

h having between them an undulating web *h*, and the plates are chamfered or beveled to a point at their free ends, somewhat beyond the end of the web. The sliders have hooks *j* projecting into the key-way, the hooks being bent in the direction in which the respective sliders are thrust by their springs. When the key is inserted into the key-way obstructed by the hooks the beveled ends of the side plates enable these plates to slide under the hooks and slightly retract the sliders, but complete retraction of the sliders is not effected until the web of the key has been pushed between the tips of the oppositely directed hooks. When the key has been fully inserted, each slider has been retracted to the extent required to disengage it from the shell *a*. Any excess movement beyond this retraction, by the use of a wrongly shaped key or other implement, will cause the shank *g* to enter the hole *m*, so that the slider will again lock the barrel. When the barrel is free it can be rotated by the key to actuate the stem *o* and the bolt or other appropriate member of the lock.

In the modification shown in Figs. 8 and 9, the sliders *p* are flat strips cut away at one edge to form a shoulder, and in the barrel there are members *r*, each having a similar shoulder, the springs *q* being lodged between the shoulders of the sliders and members *r*.

It will be clear that a single key may serve for opening two such locks, which are alike in all respects except that in one of them some of the sliders are omitted, say two or three sliders near the key entrance, but that in that case a key designed solely for actuating or setting the smaller number of tumblers will not open the lock having the full number.

It will be noted that the key entrance may be made very small, as its size can be limited to the small cross sectional area of the key.

What I claim as my invention and desire to secure by Letters Patent of the United States is:—

In a lock the combination of a shell, a barrel rotatable in said shell and having a key-way, two parallel rows of sliders mounted in said barrel at opposite sides of said key-way, said sliders having oppositely directed hooked members extending into said key-way, springs thrusting said sliders in opposite directions into engagement with

said shell, and a push-key having two parallel side plates adapted to engage said hooked members, and an undulating web between said side-plates adapted to push said members in opposite directions and retract the sliders from engagement with the shell.

In witness whereof I have signed this specification in the presence of two witnesses.

ANTOINE ANDREANI.
